UNITED STATES PATENT OFFICE.

DANIEL J. MARLOWE, OF WOBURN, MASSACHUSETTS, ASSIGNOR TO THE BABCOCK PRINTING PRESS MANUFACTURING COMPANY, OF NEW LONDON, CONNECTICUT, A CORPORATION OF CONNECTICUT.

METHOD OF PREPARING MAKE-READY ON CUTTING AND CREEASING PRESSES.

Application filed December 3, 1923. Serial No. 678,147.

My invention relates to a new method of preparing make ready for presses on which heavy paper or cardboard stock is to be cut and creased such as in making blanks for boxes, folders, and other articles of a similar nature. One of the principal objects of the present invention is to greatly reduce and in some cases to entirely eliminate the necessity for changing the printing form to compensate for the drawing in or shortening of the sheet caused by the creasing operation; or, in the alternative, of shortening the cutting and creasing die without having to remake the skeleton. It will be obvious that where a sheet passes through the press which is arranged for cutting and creasing, that the creasing rules which form the creases in the stock, take up or shorten the sheet and this action is not uniform over the whole sheet, that is to say, the action starts, to some degree, just after the leading edge of the sheet, which is held by the grippers, comes into contact with the creasing rules, and the action is more or less cumulative until the entire sheet has passed the die, and the shortening of the sheet or draw-in must be compensated for either by readjusting the printing form or readjusting the cutting and creasing die.

The object of the present invention is to reduce the amount of labor and the cost thereof in preparing the cutting and creasing press and to eliminate the idle period of either the printing or cutting or creasing press as far as possible. Other objects will be apparent from the following detailed description of the invention:

In the drawings forming part of this application,

Figure 1 is a sectional view of a cutting and creasing cylinder together with the bed and cutting and creasing die with the make ready and skeleton on, ready to run,

Figure 2 is a front elevation thereof,

Figure 3 shows a sample box blank used as an example of a blank which may be cut and creased on the press,

Figure 4 is a perspective view of a simple form of rectangular box without ends made from this blank,

Figure 5 is a diagrammatic view showing the shortening effect of the creasing rules upon the stock, and

Figure 6 is a sectional view correspond-

ing to Figure 1 but showing the method of preparing a jacket forming the subject of this application.

In Figure 1 I have shown a die 1 made up of suitable creasing rules 2 and suitable cutting rules 3 arranged to crease and cut a sheet of stock to make box blanks such as is shown in Figure 3. This die is locked up in the chase 4 which is mounted on the bed 3' of the press in accordance with the usual practice.

The jacket 5, usually of hardened steel, is placed on the impression portion 20 of the impression cylinder 19 of the press which press may be one which is especially built for cutting and creasing or it may be a printing press used for cutting and creasing. Under the jacket 5 sheets of paper 6 are inserted between the jacket and the impression portion 20 of the cylinder to pad the jacket or bring its surface sufficiently high so that the edges of the cutting rules 3 will just touch the surface of the jacket. A sheet of manila paper is then glued on the outside surface of the jacket (this is not shown in the drawing) and an impression is taken on this manila paper to get the location of each box blank on the jacket. Sheets of box board approximately the size of each separate box are then glued on the jacket, one of these blanks being represented by the bracket 7 in Figure 1 in the drawing. The edges of the cardboard are then beveled off as shown at 9, 10, 11, and 12 to correspond with the positions of the cutting rules in the die in order to allow the cutting rules to cut clear through the manila sheet and the stock without damaging it. The tops of the creasing rules 2 which are slightly below the tops of the cutting rules 3 are then inked and an impression is taken on the cardboard which was glued to the jacket so that the positions of the creasing rules are marked on the cardboard and the operator then proceeds to cut grooves in the sheets of cardboard attached to the jacket, corresponding with the positions of the creasing rules, as shown at 13.

If a sheet of stock approximately the length of a die as indicated at 14 in Figure 5, is run through the press the stock will be shortened perceptibly owing to the amount of stock that has been drawn in by the creasing rules forcing the stock into the grooves 13 of the cardboard on the jacket and the

stock will then have the appearance somewhat like 15 in Figure 5 although the shortening has been exaggerated to more clearly illustrate the fact. This cardboard glued to 5 the jacket, and in which the grooves 13 have been cut, is known as the skeleton. It will be apparent that if the stock fed to the press has been previously printed from a printing form made to conform to the finished 10 box blank, that the creases in the stock will not come in the correct positions to correspond with the printing because of the drawing in or shortening of the sheet by the creasing rules.

15 In following my method the stock is first printed by feeding it through a printing press provided with the necessary form and this is done at any time before the cutting and creasing operation takes place. When 20 preparing to run the stock on the cutting and creasing press the cutting and creasing rules are assembled to form a suitable die which is locked up in the chase and mounted on the bed of the press in the usual manner. 25 Instead of first putting on a sheet to form a skeleton as shown in Figure 1, sheets of soft board somewhat thicker than the sheet usually employed for making a skeleton are glued to the outer surface of the steel jacket 30 on the impression cylinder. These soft boards indicated at 16 in Figure 6 and which I prefer to call masks, are each large enough to cover the creases of one box blank. Each of these masks 16 will therefore come opposite 35 a set of creasing rules 17 in Figure 6 and there will be spaces 18 left between adjacent masks through which the cutting rules may pass in order to touch the surface of the jacket. Instead of cutting grooves 40 in these masks in the manner in which the grooves are cut in the skeletons under the previous methods a test sheet of the stock from which the job is to be run will be fed through the press so that the cutting rules 45 will pass through the spaces 18 between the masks and the creasing rules will press the stock into the soft mask; and because of the relative softness of the masks, the creasing rules will force the stock into the soft mask 50 and while a perfect crease will not be formed nevertheless the crowding in of the sheet into the soft mask by the creasing rules will cause the stock to be drawn in and shortened approximately the same extent as if the 55 stock had been run through on a skeleton in connection with the old method.

By having these masks somewhat thicker than the required skeleton sheet, the drawing in of the stock will shorten the sheet 60 approximately the same as if the sheet had been run through a press provided with a grooved skeleton even though the creases are not as sharp as when the stock is run with a skeleton.

65 After the above operations have been car-

ried out the operator proceeds to shorten the cutting and creasing die to compensate for the drawing in of the stock by the creasing rules operating with the masks, so that in the final die the cutting and creasing rules 70 will be in position to correspond on the finished sheet with the printing; and this is a simple operation because it has been unnecessary to cut any grooves in the masks by hand and the operation of cutting grooves 75 in the skeleton as a preliminary step is entirely eliminated.

After the die has been shortened so that it will correspond in the final operation with the position of the printing, the operator 80 will then strip the masks 16 from the jacket and will then glue on to this jacket the usual manila sheet and proceed to make the skeleton to conform with the shortened die in the same manner as in former practice. If he 85 prefers he may remove the jacket which has the mask on and replace it with another jacket to which the manila sheet for the skeleton has been glued. From the above it will be apparent that it is not necessary to 90 first make a skeleton, then shorten the die and again make a skeleton to conform with the shortened die, so that one very expensive and tedious step in former methods has been 95 eliminated.

100 In some cases it may be desirable to proceed with the make ready for the cutting and creasing press before the printing form has been made up. In such cases the printing press does not have to remain idle during any part of the preparation of the cutting and creasing press. In this case the operator will take an impression on the manila sheet as first described and then cut out the lines corresponding with the positions of the cutting rules. He will then attach the temporary masks to the paper on the jacket as described above, and make the test impression upon the sheet of stock to 105 determine the draw-in on the sheet. He will then shorten the cutting and creasing die, strip the masks from the cylinder and proceed to complete the skeleton. The printing form may then be assembled to correspond with the positions of the blanks on the test sheet of stock so that the printing press is not brought into use until after the skeleton for the cutting and creasing press has been completed.

Having described my invention what I 110 claim is:

1. The method of preparing make ready for cutting and creasing which includes as a part of the method the operation of attaching a mask or masks of thick and compressible material to the jacket of the cylinder of the press and running a sheet of stock between the cutting and creasing die and said mask whereby the stock is pressed into 115 said mask by the creasing rules of the die to 120 said mask by the creasing rules of the die to 125 130

determine the amount of draw-in on the stock by the creasing rules.

2. The method of preparing make ready for cutting and creasing which includes as a part of the method the operation of attaching a mask or masks of thick and compressible material to the jacket of the cylinder of a press with slots therein to permit the cutting rules to pass freely to the surface of the jacket, then running a sheet of stock between said cutting and creasing die and said mask whereby the stock is pressed into said mask by the creasing rules of the die to determine the amount of draw-in on the stock by the creasing rules.

3. The method of preparing make ready for cutting and creasing which includes assembling the cutting and creasing die, attaching a mask or masks of compressible, thick material to the jacket of the cylinder of the press, running a sheet of stock be-

tween the die and said mask or masks to determine the approximate draw-in of the stock by the creasing rules, and then shortening the cutting and creasing die for the purpose set forth.

4. A method of preparing a cutting and creasing matrix which includes as part of the method a substitution of a mask for the skeleton of thicker and softer material than that from which the skeleton is formed, and running a preliminary test with said mask by subjecting it to the impression of a cutting and creasing die to form an impression on said mask to determine by the drawing action on the stock the exact size of the die necessary to conform with the printed sheet.

Signed at the city of New York, in the county of New York and State of New York this 13th day of November 1923.

DANIEL J. MARLOWE.
